UNITED STATES PATENT OFFICE.

CHARLES M. REYNOLDS, OF BRIGHTON, MASSACHUSETTS, ASSIGNOR TO THE LAMSON COMPANY, OF BOSTON, MASSACHUSETTS, A CORPORATION OF NEW JERSEY.

CASH-CARRIER FOR CABLE-CARRIER APPARATUS.

1,200,868.

Specification of Letters Patent.

Patented Oct. 10, 1916.

Application filed March 2, 1915. Serial No. 11,446.

To all whom it may concern:

Be it known that I, CHARLES M. REYNOLDS, a citizen of the United States, residing at Brighton, in the county of Suffolk 5 and State of Massachusetts, have invented certain new and useful Improvements in Cash-Carriers for Cable-Carrier Apparatus, of which the following is a specification.

This invention relates to carriers for 10 cable-carrier apparatus, and more especially to carriers such as are shown in the patent of Geo. A. Amsden, No. 960617, dater June 7, 1910.

One of the objects of the present invention 15 is to simplify the construction of carriers of this description.

Another object has been to cheapen the cost of their production; while still another has aimed at making the construction more 20 durable and better able to withstand the severe usage to which such carriers are subjected in practice.

These and other objects of my invention 25 will be hereinafter referred to and the novel elements and combinations of elements, whereby said objects may be attained will be more particularly pointed out in the claim appended hereto.

In the accompanying drawing, which 30 forms a part hereof and in which like reference characters designate like parts throughout the several views, I have exemplified a preferred construction; but as I am aware of various changes and modifications which 35 may be made herein without departing from the spirit of the invention, I desire to be limited only by the scope of said claim.

Referring to the drawing: Figure 1 is a 40 plan or top view of the carrier. Fig. 2 is a side elevation of the same. Fig. 3 is a bottom view of the improved carrier. Fig. 4 is a bottom view of the receptacle or cash box proper; the fiber bottom or guide plates having been removed. Fig. 5 is a plan view 45 of the upper of these fiber plates. Fig. 6 is a similar view of the lower fiber plate showing the bottom sheet-metal guide plate attached thereto; and Fig. 7 is a section taken on line VII—VII of Fig. 6.

50 The carrier may comprise the usual sheet-metal cash box 1; with a preferably pivotally mounted cover plate 2 adapted to be pressed open by a spring 3, after the latch 4 has been rotated counter-clockwise as 55 viewed in Fig. 1.

The carrier may be fitted with the usual deflecting guide 5, and a cable-gripping device comprising the pivotally mounted jaw 6 and coacting jaw 7, which for simplicity, in the present case, is shown as being fixedly 60 mounted upon the bottom of the box 1.

As viewed in Fig. 2, a fiber plate 8, upon which the carrier normally rides when the rails of its track are disposed in the same horizontal plane, is secured to the bottom 65 of the receptacle 1, and below this plate 8, which is shown in plan in Fig. 5, is a second fiber plate 9, secured thereto as shown in Figs. 2 and 6. The plates 8 and 9 are respectively recessed or apertured as at 10 and 70 11, to accommodate the grip mechanism; and the sheet metal guide or bottom plate 12, provided with its guide lugs 13 and 14, is also slotted somewhat arcuately, as at 15, to accommodate the grip parts 7 and 6, and 75 permit the latter to move to its dotted line position, designated 6' in Fig. 3. These carriers are apt to be subjected to rather rough usage and for this reason it has been found to be exceedingly desirable to form this bottom plate 12 from sheet-metal, such as rolled 80 plate or the like; and it has further been found inexpedient to form the metal parts of the carrier, such as the box 1, or plate 12, which are exposed to the hands of the user, 85 of steel, even though the latter be nickel-plated; since in time the perspiration from the hands will usually result in the formation of rust spots and discolorations. The box 1, cover plate 2, and bottom plate 12, 90 are hence preferably made of some suitable composition which is rust-proof in character and of reasonably high tensile strength, and it is for this reason that the metal is usually drawn or rolled sheet metal, rather than 95 cast. These considerations are of importance in view of the novel fastening means, now to be described, which are used for connecting the bottom plate 12, fiber plates 8 and 9 and box 1, rigidly together.

100 Referring more particularly to Figs. 6 and 7, it will be observed that cylindrical bosses 16, project upwardly from the plate 12; and in the present and preferred construction, these bosses are five in number. They are 105 formed from small cylindrical blocks, cut from a metal rod, and these blocks are then integrally united to the plate 12 by welding. This welding is preferably effected by means of what is known as an electrical spot 110

welding machine; and the union thereby effected between said blocks and the bottom plate 12 is so strong as to be able to resist heavy jars and distortional stresses, when 5 the carrier is in use. The said bosses 15, after they have been welded to the bottom plate, are drilled and tapped for the reception of the threaded lower extremities of the shoulder bolts 17, one of which is shown in 10 position in one of the studs or bosses 16, in Fig. 7. The term shoulder bolt is of course, to be understood as comprehending a bolt provided with a shoulder part of any suitable description which shall adapt said bolt 15 for co-action with its corresponding boss 16 in the manner indicated in the construction given by way of exemplification.

Assuming that the parts of the carrier have been assembled to the extent shown in 20 Fig. 4, the plate 8 will now be placed in position upon the bottom of the box 1, so that the holes 18 therein, coincide with the holes 19 in the bottom of the box. One or more of the shoulder bolts 17 may now be introduced 25 through the apertures or holes 18 and 19 and, when the plate 12 with the fiber plate 9 securely mounted thereupon (as by means of a driving engagement between the studs 16 and this fiber plate) are emplaced upon the 30 plate 8, as shown in Fig. 3, the shoulder bolt or bolts 17 may then be screwed into the studs or bosses 16, to effect an exceedingly rigid connection between the several parts.

By reason of the fact that the studs 16 35 are integrally and autogenously united to the plate 12, the connecting or joining parts are made strongest at the points where they are apt to be subjected to the greatest stress, namely,—in the plane of the upper side of 40 the plate 12. This construction is hence far stronger than would be the case if, for example, the studs 16 were not integrally united to the plate 12, but were inserted into holes therein, with their exposed lower ends 45 peened or burred into locking engagement with the plate.

A further advantage residing in the con-

struction exemplified in the drawing is that the box is rendered more slightly in appearance; since as shown in Fig. 3 the means for 50 connecting the box, its fiber plates and bottom or guide plate, are wholly concealed, and the bottom plate presents a smooth unbroken surface, save for the slot 15.

The carrier is thus rendered more durable 55 and slightly and in addition to this the cost of its construction is reduced. At the same time the great advantage of making the bottom plate of rolled metal, or the like, is retained which, of course, would not be the 60 case, were this bottom plate to be made of cast metal.

Having thus described my invention, what I claim is:

In a cash carrier for cable carrier apparatus, the combination of a receptacle for cash or the like, with a guide plate for said receptacle having means to engage one side of the rails of the track upon which the carrier rides, said guide plate being of sheet 70 metal, interiorly threaded bosses, integrally and autogenously united to said guide plate and projecting from the side thereof toward said receptacle, non-metallic rail engaging material between said receptacle and 75 its guide plate and adapted to coact with the latter to retain the carrier in place upon its track, and shoulder bolts connecting said receptacle, said non-metallic material and said guide plate rigidly together, said bolts being 80 threaded into the integrally united bosses of said guide plate up to the shoulders thereof, whereby to render the thereby connected parts, while separable,—nevertheless rigid and substantially unyielding to the lateral 85 stresses to which they are subjected when the carrier is in use.

In testimony whereof I have affixed my signature, in the presence of two witnesses.

CHARLES M. REYNOLDS.

Witnesses:

PATRICK J. RYAN,
JAMES F. MULVANEY.
